PLAYGROUND CLIMBER

Robert S. Wormser, Hillsdale, Mich., assignor to Game Time, Inc., Litchfield, Mich., a corporation of Michigan

Filed Nov. 26, 1968, Ser. No. 14,678

Term of patent 14 years

Int. Cl. D21—04

U.S. Cl. D34—5

FIG. 1

FIG. 2

FIG. 3

FIG. 4

FIG. 1 is an elevational view of a playground climber in accord with my new design,

FIG. 2 is an elevational view as taken from the left of FIG. 1.

FIG. 3 is an elevational view of my new design as taken from the right of FIG. 1, and

FIG. 4 is a plan top view of the design.

I claim:

The ornamental design of a playground climber, substantially as shown.
